CALENDAR

Lester L. Vierling, Oradell, N. J., assignor to
 American Colortype Company, New York, N. Y.,
 a corporation of New Jersey

Application August 16, 1935, Serial No. 36,482

1 Claim. (Cl. 40—119)

The present invention relates to calendars and embodies, more specifically, an improved form of calendar by means of which artistic or advertising indicia may be displayed effectively with the usual calendar indicia, the hinged pages of the calendar serving as a means for receiving calendar indicia upon one side thereof, and upon the other side thereof, artistic or appropriate advertising matter.

10 More particularly, the invention comprises a calendar in which the hinged pages may be effectively supported in two positions to resemble a substantially flat object, the pages being so positioned as to maintain them effectively in the 15 above relationship and prevent the bowing or slipping thereof due to gravity.

Calendars have been constructed heretofore with the pages thereof provided with calendar indicia upon one side and artistic or advertising 20 matter upon the other side, in some of these forms of calendars the pages being supported in an upwardly swung position by means of paper clips. In accordance with the present invention, a construction is proposed by means of which 25 the calendar pages may be supported in an upwardly swung position by a portion of the cover or back of the calendar in an artistic and attractive fashion. By means of the particular construction of the present invention, the pages 30 which have been swung into an upward position in order that subsequent calendar pages may be displayed, are slightly tensioned by causing them to support, partially, the weight of the calendar, thus maintaining them substantially flat.

35 Particular objects and advantages of the invention will appear from a more detailed description thereof in connection with the accompanying drawing, wherein

Figure 1 is a plan view of a calendar constructed in accordance with the present invention and folded into a convenient book or pamphlet form. Portions of this figure have been broken away and shown in section;

Figure 2 is a plan view of the calendar in open position with certain of the pages thereof swung upwardly and positioned against the calendar back or cover, being held in such relationship in a manner to be described presently;

50 Figure 3 is a view in section, taken on line 3—3 of Figure 2, and looking in the direction of the arrows;

Figure 4 is a partial view in section, taken on the line 4—4 of Figure 2 and looking in the 55 direction of the arrows; and

Figure 5 is a partial view, similar to the lower portion of Figure 2, and showing a slightly modified form of calendar wherein a single tab is utilized to maintain the lower leaves against the cover.

The calendar, in accordance with the present invention, is formed with a cover which is hinged at 10 and provided with an upper portion 11 and a lower portion 12. Pages 13 are hinged intermediate their ends at 10 and, upon the outer 10 faces thereof (as considered when the upper portion is suspended and the pages are suspended from the hinge 10) suitable calendar indicia is placed. In Figure 2, the outer face of one of the pages is shown at 14, while the inner face 15 of the preceding page is shown at 15, this face being exposed by reason of the fact that such preceding page has been swung upwardly about the hinge 10 and maintained in such upper position by means of tabs 16 and the supporting 20 nail which form an important part of the present invention.

These tabs are stamped out of the material of the cover along the line 17 in Figure 1, and thus permit the upwardly swung pages to be slipped 25 under the tabs to assist in maintaining the pages which have been so positioned in a substantially flat condition against the calendar back or cover. In the preferred form of the invention, it is proposed to place attractive and artistic subject 30 matter upon the backs 15 of the pages and ornament the tabs 16 in such fashion as to constitute a pleasant and agreeable portion of the artistic subject matter displayed upon the calendar back and pages.

In order that the lower pages may be maintained in flat relationship to the cover, tabs 18 are formed in the lower portion of the cover and the bottom edges of the suspended pages are inserted under these tabs, as indicated in Figure 2. 40

In order that the pages which have been swung into an upper position and inserted under the tabs 16 may not bow outwardly and thus eventually slip back into the lower position, the pages and cover are apertured while in the closed position 45 shown in Figure 1. In such position, the apertures in the pages and the cover are aligned. As a result, when the calendar is suspended from an object which extends through these apertures, each subsequent aperture in the calendar pages 50 13 to be placed over the supported object is spaced a shorter distance from the hinge 10 than the previous aperture, thus subjecting each page to a slight tension by reason of the fact that it helps to support the weight of the calendar upon the 55

projection or hook. As a result, the pages which have been swung into an upper position are supported effectively in flat relationship with respect to the calendar cover or back. Figure 4 5 illustrates the manner in which the apertures in the upwardly swung pages are progressively nearer the hinge and thus are subjected to a portion of the weight of the suspended calendar.

In the construction shown in Figure 5, a slightly modified form of calendar is shown wherein the tabs 18 have been replaced by a single wide tab 19 which may be positioned intermediate the side edges of the cover and, incidentally, may cover the apertures in the calendar leaves. In 15 such construction, the apertures may be punched with the lower half of the cover removed from under the punch so that no aperture would be formed in this cover portion.

From the foregoing, it will be seen that the 20 present invention provides a highly attractive calendar which may be folded, for transmittal, into book or pamphlet form and artistically decorated. The arrangement and positioning of the 25 pages is such as to combine, with the calendar indicia, subject matter of an advertising or artistic nature in such fashion as to present the lat-

ter in a pleasing and effective manner. While the invention has been described with respect to the specific construction shown in the accompanying drawing, it is not to be limited save as defined in the appended claim.

I claim:

A calendar having a cover folded intermediate the ends thereof and provided with hinge means at the fold, pages formed by sheets folded intermediate the ends thereof and hinged at the hinge means to form pages having outer and inner sides in a suspended position, calendar indicia on the outer sides of the pages, artistic matter on the inner sides of the pages and adapted to be viewed when swung about the hinge into an upper position, tabs stamped out of the material of the cover at each end thereof to support the pages flatwise against the adjacent portion of the cover, and apertures in the cover and pages, said apertures being aligned in the closed position of the 20 pages and cover, whereby the apertures of the 25 upwardly swung pages will be spaced successively nearer the hinge and thus subject the upwardly swung pages to a portion of the weight of the calendar.

LESTER L. VIERLING.
